UNITED STATES PATENT OFFICE

ELLWOOD V. CROSS, OF WASHINGTON, DISTRICT OF COLUMBIA

BELL RINGER

Application filed July 9, 1929. Serial No. 376,993.

This invention relates to improvements in bell ringers for locomotives, and has as its primary object the dependable power ringing of a bell, and as a secondary object the definite and accurate regulation of the speed or rate of such ringing.

With these and further objects in view as will in part hereinafter become apparent and in part be stated, the invention comprises 10 certain novel constructions, combinations, and arrangements of parts as subsequently specified and claimed.

In the accompanying drawings,—

Figure 1 is a view in front elevation of 15 a fragment of a locomotive having applied thereto an embodiment of the present invention, parts being broken away and seen in section.

Figure 2 is a longitudinal, vertical section 20 through the power cylinder, parts being seen in elevation, and the parts being seen on an enlarged scale.

Figure 3 is a sectional elevation of the 25 trip valve for controlling the steam supply to the cylinder.

Referring to the drawings by numerals, 1 indicates the usual locomotive bell mounted in any well known manner, as, for example, on a supporting bracket 2 fixed to the head 30 of the locomotive boiler. A hammer 3 is carried by an actuating lever 4, pivoted at 5, in position for having the hammer appropriately strike the bell 1 when the lever 4 is swung on the pivot 5 with the required oscillations. A cylinder 6 is fixed by an appropriate bracket 7 to the head of the locomotive boiler adjacent the lever 4, and is provided with a piston rod 8 having a pin and slot connection 9 with the lever 4 for actuating the latter. The piston rod 8 penetrates one end of cylinder 6, and the opposite end is penetrated by the steam line 10 leading from the dome or other source of supply through the usual cab-located control valve, not illustrated. Within the cylinder 6 piston rod 8 is provided with an appropriate head 11 having the usual piston packing and engaged at its face remote from the intake from line 10 by a return spring 12. Spring 12 is disposed between the piston head 11 and

the remote head of the cylinder, and is tensioned according to the rate of strokes desired. The greater the tension of spring 12, the more rapid will be the strokes, and, conversely, the lower the capacity or more sluggish the spring 12, the slower will be the strokes, it being intended to substitute a different spring 12 whenever the rate of stroke is to be changed.

However, an appropriate varying of tension of spring 12 may be depended upon for varying the rate of stroke, as, for example, when the head of the cylinder is threaded in place, as illustrated in Figure 2, the greater or less extent of the threading on of the head, the greater or less extent the tensioning of the spring. Obviously, the substitution of different springs is preferred as a more dependable means of control. At the intake end portion of the cylinder 6, a cushioning spring 13 is located 70 to prevent excessive return movement of piston 11.

An exhaust port or ports 14 is or are formed through the side of cylinder 6, and the piston-rod-penetrated head of the cylinder is provided with an air equalizer port 15 for allowing free play of piston 11 without air compression or formation of vacuum. Also, the head of cylinder 6, having the port 15, is preferably substantially thickened, and may be thickened relatively to a greater extent than indicated in the drawings to avoid wear incident to sliding contact of piston rod 8. Of course, leakage through the cylinder head about the piston rod 8 does not represent a 85 disadvantage, but may supplement the functioning of port 15. However, excessive wear is to be avoided to maintain the parts in proper alignment.

An intake control valve 16 is arranged in 90 the length of pipe 10 and located to cooperate with the other parts. The valve 16 is provided with an operating stem 17 and an appropriate head 18, the latter cooperating with a valve seat 19. Valve seat 19 is of 95 considerably larger gauge than the gauge of pipe 10. For example, if the pipe 10 be of say three-eights inch size, the valve 16 should be an inch and a quarter valve, and the pipe connections for pipe 10 should be bushed 100.

down and up to the pipe so that a very quick or brief opening of the valve head 18 from its seat 19 will admit a requisite charge of steam to effect the results desired while a 5 comparatively small pipe 10 is employed. A bracket 20 is preferably carried by the housing of valve 16, and a lever 21 is pivoted to the bracket and arranged to pivotally engage the stem 17. The free end portion of 10 lever 21, as seen in Figure 1, is engaged by a push rod 22, and a stop 23 carried by said push rod. The push rod preferably extends through an appropriate opening in the end portion of lever 21, so that the stop 23 will 15 be sure to move the lever 21 from the dotted line position to the full line position of Figure 1 under the impulses of the rod 22. The rod 22 is pivoted at 24 to lever 4, and may be sustained by any additional guiding means 20 desired, but not illustrated. Thus, upon the return stroke of the lever 4, the lever 21 will be swung from the dotted line position of Figure 1 to the full line position thereof, whereupon the valve head 18 will be moved 25 from its seat 19 by the return stroke of the lever 4.

In operation, the locomotive engineer merely turns on the steam pressure to the pipe 10 to ring the bell 1, and the ringing 30 will continue until the engineer cuts off the supply of steam. The parts normally stand at rest, as seen in Figure 2, and in full lines in Figure 1. The first impulse of steam, therefore, passes freely into cylinder 6 and 35 drives the piston 11 back to the bell ringing position indicated in dotted lines in Figure 1. When the piston reaches this position, the ports 14 will be exposed, and the exhausted steam will allow a return thrust of 40 the piston under the impulse of the then compressed spring 12. However, meanwhile, as the piston 11 moved to the bell ringing position under the steam pressure, that very movement causes the rod 22 to move to 45 the releasing position of lever 21, so that the valve head 18 could seat itself under the action of the return spring 18'. Thus, the valve head 18 was seated on the seat 19 before the actual time of stroke of the hammer 13 50 against bell 1; and the exhausting of the expanding steam through ports 14 left the cylinder 6 in condition for the free return stroke of piston 11. The return stroke will progress as far as permitted incident to the 55 fact that during such return stroke the lever 21 will be swung by the action of the rod 22, and a new impulse of steam admitted. Thus, the piston head 11 and rod 8 and connected parts are reciprocated continuously until the 60 supply of pressure is cut off from pipe 10.

What is claimed is:—

1. In bell ringing apparatus for locomotives, the combination of a pivotally mounted hammer, a piston rod pivotally engaging the hammer for actuating the same,

a cylinder into which said piston rod extends, a piston head within the cylinder a spring for effecting return stroke of the piston, retracting the hammer from its bell ringing position, means for delivering fluid under pressure to the cylinder for imparting the out stroke to the piston to cause the hammer to strike the bell, a valve connected to be unseated by parts moved by the piston for delivering intake of fluid under pressure to said cylinder when the hammer is moving to retracted position, and means connected to the hammer for unseating the valve as the hammer is being retracted, the cylinder being provided with an exhaust port located 70 relative to the range of travel of the piston for exhausting substantially at the terminus of the outer stroke, before the hammer strikes the bell, and the valve actuating means being proportioned so that the steam supply valve will be seated prior to attainment by the piston of the position to exhaust. 75

2. In bell ringing apparatus for locomotives including a bell and bell ringing means, the combination of a cylinder having an exhaust port, means for delivering fluid under pressure to the cylinder, means in the cylinder adapted to be actuated by such fluid under pressure for ringing the bell by the bell ringing means, and means actuated by the bell ringing means for controlling the delivery of fluid under pressure to the cylinder. 80

3. In bell ringing apparatus for locomotives including a bell and bell ringing means, the combination of a cylinder having an exhaust port, means for delivering fluid under pressure to the cylinder, means in the cylinder adapted to be actuated by such fluid under pressure for ringing the bell by the bell ringing means, and means actuated by the bell ringing means for controlling the delivery of fluid under pressure to the cylinder, said control means including a valve of substantially larger capacity than the cross sectional capacity of the fluid supply means. 100

4. In bell ringing apparatus for locomotives including a bell and bell ringing means, the combination of a cylinder having an exhaust port, means for delivering fluid under pressure to the cylinder, means in the cylinder adapted to be actuated by such fluid under pressure for ringing the bell by the bell ringing means, and means actuated by the bell ringing means for controlling the delivery of fluid under pressure to the cylinder, said control means including a valve of substantially larger capacity than the cross sectional capacity of the fluid supply means, and the valve actuating means being proportioned and located to effect seating of the valve for an appreciable period prior to the parts reaching a condition for exhausting 110 120 125 130

the fluid under pressure through said exhaust port.

5. In bell ringing apparatus for locomotives, the combination of a pivotally mounted hammer, a piston rod pivotally engaging the hammer for actuating the same, a cylinder into which said piston rod extends, a piston head within the cylinder, a spring for effecting return stroke of the piston, a conduit for delivering fluid under pressure to the cylinder for imparting the out stroke to the piston, and a valve in said conduit connected to be unseated by parts moved by the piston for delivering intake of fluid under pressure to said cylinder, the cylinder being provided with an exhaust port located relative to the range of travel of the piston for exhausting substantially at the terminus of the outer stroke, and the valve actuating means being proportioned to seat the valve prior to attainment by the piston of the position to exhaust, and means for cushioning the return stroke of the piston.

6. In bell ringing apparatus for locomotives, the combination of a pivotally mounted hammer, a piston rod pivotally engaging the hammer for actuating the same, a cylinder into which said piston rod extends, a piston head within the cylinder, a spring for effecting return stroke of the piston, a conduit for delivering fluid under pressure to the cylinder for imparting the out stroke to the piston, a valve in said conduit connected to be unseated by parts moved by the piston for delivering intake of fluid under pressure to said cylinder, the cylinder being provided with an exhaust port located relative to the range of travel of the piston for exhausting substantially at the terminus of the outer stroke, and the valve actuating means being proportioned to seat the valve prior to attainment by the piston of the position to exhaust, the piston-return spring being proportioned to return the piston sufficiently for fully opening the valve.

7. In bell ringing apparatus for locomotives including bell ringing means, the combination of a cylinder having an exhaust port, means for delivering fluid under pressure to the cylinder, means in the cylinder adapted to be actuated by such fluid under pressure for operating the bell ringing means, a valve controlling the intake of fluid under pressure to said cylinder, a trip lever for actuating said valve, a link connected to and actuated by the bell ringing means for imparting tripping movement to said lever for opening the valve and adapted to allow seating of the valve prior to a position of the parts permitting exhaust through said exhaust port, and means for effecting a return movement of the parts after closing of said valve and exhausting of said fluid.

In testimony whereof I affix my signature.

ELLWOOD V. CROSS.
